DESIGN FOR A DISPLAY SIGN OR SIMILAR ARTICLE

Ernest R. Erickson, Des Moines, Iowa

Application May 11, 1936, Serial No. 62,596

Term of patent 7 years

To all whom it may concern:

Be it known that I, Ernest R. Erickson, a citizen of the United States and a resident of Des Moines, in the county of Polk and State of Iowa, have invented a new, original, and ornamental Design for a Display Sign or Similar Article, of which the following is a specification, reference being had to the accompanying drawing, forming part thereof.

The figure is a perspective view of a display sign or similar article illustrating my design. The reverse side of the sign is substantially the same as the side illustrated.

I claim:

The ornamental design for a display sign or similar article substantially as shown and described.

ERNEST R. ERICKSON.
